UNITED STATES PATENT OFFICE.

HARRY S. MYERS, OF VAN, PENNSYLVANIA.

WINDING DRUM.

1,411,061.

Specification of Letters Patent. Patented Mar. 28, 1922.

Application filed January 31, 1922. Serial No. 532,992.

To all whom it may concern:

Be it known that I, HARRY S. MYERS, a citizen of the United States, residing at Van, in the county of Venango and State of Pennsylvania, have invented certain new and useful Improvements in Winding Drums, of which the following is a specification.

This invention relates to winding drums, and more particularly to a novel construction of drum and mounting in which the drum is composed of a number of parts so chosen as to produce maximum strength in the assembled structure and a maximum of winding capacity with a minimum of width.

15 The particular adaptation selected for the purpose of illustration is a drum designed for use in hoisting machinery, in which certain of the parts are placed under heavy strain and in which there is a demand for 20 maximum winding capacity for a given available width of space to be occupied by the drum and its wound cable.

25 The object of the invention is the production of a light construction of drum which will have great strength and winding capacity. Another object is the production of a drum which will have maximum width for a given width of space to be occupied by the hoisting machinery.

30 Another object of the invention is the production of a drum in which the strains will be distributed and in which the parts are so formed as to receive heavy strains without danger of injury to the drum parts

35 or their relative displacement. A further object is the production of a drum of parts which when assembled will act to securely hold the drum intact and the parts from relative displacement. A still further object is the provision of novel means for holding the drum parts when assembled against sliding movement upon the shaft upon which it is mounted. A still further object is the provision of a mounting for the shaft and 45 drum, which will maintain them in perfect alignment with the other elements of the hoisting machine.

Another object of the invention is the mounting of the drum drive gear and the 50 brake track upon the drum ends, and a still further object is the provision of novel means for mounting the drive gear upon the drum end.

55 Other objects and advantages of the invention will hereinafter appear in the following description and the novel features

thereof will be particularly pointed out in the appended claims.

In the drawings,

Figure 1 is a longitudinal sectional view 60 through the drum but showing the drum shaft in full.

Figure 2 is a sectional view taken upon the line 2-2 of Figure 1, and

Figure 3 is a perspective of one of the 65 bearing elements used in the drum mounting.

Like reference characters indicate like parts throughout the figures of the drawings.

It will be understood that the invention may be varied in its details of construction 70 and that the specific embodiment illustrated and described herein is only indicative thereof; the specific embodiment, however, is one which has been found to be practical in its construction and operation.

75 The drum consists essentially of a shaft 10 upon which are individually keyed two stepped hubs 11, 11, supporting a drum cylinder 12. Secured to the outer faces of the hubs are end disks 13 and 14, to which are 80 respectively attached the drum gear 15 and brake track 16. The shaft is mounted in bearings 17, 17, fitting closely the disks 13 and 14, and these bearings are carried by the framework of the hoisting machinery. 85 These parts will be specifically described and their individual functions pointed out, after which a recital of their conjoint operation will be given.

90 The shaft 10 is of a length equal to the maximum width of space which could be allowed in a hoisting machine combination of elements to the drum and its necessary parts. It is mounted in the bearings 17, 17, and its ends are flush with the ends of the 95 bearings. In the shaft 10 two key grooves 18, 18, are cut, and in the bore of the hubs 11, similar and correspondingly located grooves are provided. Keys 19, 19, securely hold the hubs against rotation upon the 100 shaft.

105 The hubs are stepped and at 20 are machined to provide a support for the ends of the drum cylinder 12, these parts being held together by a driving fit. Upon the shaft 10 and between the bearings 17 and hubs 11 are the end disks 13 and 14 of the drum, securely held against the extended outer faces of the hubs by the rods 22 passing through both disks and both hubs and provided with nuts upon their projecting ends.

110 It will be noted that the disks lie against

the ends of the keys 19 and thereby conjointly hold the hubs against any sliding movement upon the shaft 10. It will also be noted that the disks have their outer 5 faces substantially abutting the inner ends of the bearings 17, and thereby hold the shaft from any sliding movement within the bearings.

The gear 15 is formed with an attaching 10 web 23 of irregular shape, as shown by the dotted lines in Figure 2, which is secured to the disk 13 by bolts 24. The web 23 defines a projecting portion 25, which in the rotation of the drum just clears the 15 supporting framework 26 of the hoist. It also defines a shoulder 27 of a width equal to the thickness of the disk 13. This disk fits within the gear 15 with its circumference frictionally engaging the shoulder 27.

20 It will be seen that the long bearing of the hub 11 upon the shaft 10 insures true vertical positioning of the disk 13, which is held in close contact with the extended outer face of the hub. The drum cylinder in 25 driving fit with the steps of the hubs and held to the hubs by the connecting rods 22 causes these hubs to support each other in a true right angular position to the shaft 10. The fitting of the disk within the gear 30 in frictional contact and the bolting of these parts together causes the gear to be held in a true vertical position and enables it to be located in a position to just clear the parts of the frame work of the hoist, of which it is 35 a part.

The disk 14 is, in a like manner, secured to its hub, but is larger than the disk 13. It has securely attached to its outer face by bolts 28 a brake track or drum 16, consisting 40 of an attaching web 29, a band track 30 and a flange 31. The flange and the outer edge of the disk constitute holding means for the brake band, which acts in conjunction with the band track to form the rotating 45 portion of a brake.

It will be seen that, in a manner similar to that described in connection with the disk 13 and its associated parts, the disk 50 14 and brake track are held in a true right angular position with respect to the shaft 10 and with the outer edge of the flange 31 just clearing the parts of the hoist framework.

A cable may be attached to the drum in 55 any suitable manner; I have chosen to show for this purpose a slanted aperture 32 in one end of the drum. The shaft bearings which I have selected for use with my novel drum construction comprise an extended bearing 60 portion with attaching legs extending in opposite directions from one end thereof and designated by the numeral 33. That portion of the bearing, indicated by 34, beyond the legs 33 is of a length slightly 65 greater than the combined width of the web

23 and the gear portion 25, for a purpose hereinbefore set forth. The numeral 35 represents lubrication cups.

The operation of the drum as a portion of a hoisting machine is as follows: Power is 70 applied to the gear 15 from a driving pinion and transmitted to the disk 13 through the medium of the frictional fit of the disk with the gear and the bolts 24. The liability 75 of shearing the bolts 24 is reduced to a minimum by this mounting of the gear upon the disk and advantage taken of the full available width of the drum end for the gear. The strain upon the disk 13 is taken by the hub 11 and transmitted to the shaft 10 80 through the key connection between the shaft and hub. From the shaft 10 it is transmitted to the hub upon the opposite side of the drum and hence to the disk 14 and its associated parts. It is to be noted that no 85 torsional strain is placed upon the drum cylinder or the rods 22, these parts serving only to hold the disks and their associated elements together and in true angular position with relation to the shaft 10, necessary 90 to a smooth and efficient operation of a hoist.

It will be appreciated that the construction of drum shown and described causes the power strain to be placed upon the parts 95 best able to carry them, and that it secures a maximum width of cable winding space to a given effective width of framework. It secures in a marked degree the advantages and accomplishes the objects set forth in 100 this specification as well as others ancillary thereto.

Having described my invention, what I claim as new and desire to secure by Letters Patent is:

1. In a hoist machine, a frame having aligned bearings, a shaft in said bearings, and a drum rigidly secured to said shaft and having its ends held in position by said bearings, said ends having outwardly projecting circumferential portions forming, respectively, a drive gear and a brake track and projecting over said bearings.

2. An end of a hoist drum comprising a stepped hub, a disk secured to the hub, and 115 a gear attached to said disk, the disk lying within a shouldered portion of said gear with its face in a common plane with the edge of the gear and the face of said hub.

3. An end of a hoist drum comprising a 120 skeleton gear having an attaching web defining a circular angled recess with the gear body, a disk attached to said web and frictionally held within the recess of said gear, and a stepped hub secured to said disk, the 125 contacting faces of said disk and hub lying in a plane with the edge of the gear.

4. A winding drum comprising a shaft, hubs keyed to said shaft, a drum cylinder rigidly supported by said hubs, and end 130

disks secured to said hubs and abutting the ends of the keys, whereby the drum is held against rotation and against sliding movement upon said shaft.

5 5. A winding drum comprising a shaft, stepped hubs secured to said shaft by keys, a drum cylinder rigidly supported upon said hubs by a driving fit with the step thereof, disk ends for said drum abutting the keys 10 of said shaft to prevent sliding movement between the drum and shaft, and means for clamping the disks, hubs and cylinder together.

6. A winding drum comprising a shaft 15 provided with a pair of key grooves, stepped hubs on said shaft having corresponding key grooves throughout their length, keys in said grooves, end disks secured to said hubs and abutting the ends of said keys, a 20 drum cylinder supported by said hubs, and means for clamping the hubs, disks and cylinder together.

7. In a hoist machine, a frame carrying 25 aligned bearings, a shaft in said bearings, a drum secured to the shaft and comprising a cylindrical drum body and end members having inwardly projecting hubs supporting said body and outwardly projecting circumferential portions forming, respectively, 30 a drive gear and a brake track, said bearings abutting the faces of said end members to maintain the drum spaced in said frame.

8. In a hoist drum and mounting, spaced frame members carrying aligned bearings, a drum shaft mounted in said bearings, and 35 a drum rigidly secured to said shaft comprising end members having inwardly projecting hubs and outwardly projecting circumferential flange portions, a tubular drum body on said hubs and means for securing said drum elements to each other, one of said flanged portions being provided with teeth to form a drive gear for said drum and the other of said flange portions constituting a brake track, and the bearings 40 on said frame members being extended into the cupped drum ends defined by said flanged portions to maintain said drum spaced between said frame members.

9. A hoist drum comprising end members 50 having inwardly projecting hubs forming extended shaft engaging elements and having outwardly projecting circumferential portions constituting, respectively, drive and 55 brake elements, shoulders on said end members, a tubular drum body supported by said shoulders, means for securely holding said end members and tubular body together, a shaft mounted in said hubs, and means for securely holding said shaft against movement in said hubs.

In testimony whereof I affix my signature.

HARRY S. MYERS.
